UNITED STATES PATENT OFFICE.

GENUINO ALESI, OF WILMERDING, PENNSYLVANIA.

VALVE AND OPERATING MECHANISM THEREFOR.

Application filed April 15, 1925. Serial No. 23,370.

This invention relates to improvements in drain cocks and means for operating the same.

The primary object of this invention is 5 the provision of an improved valve mechanism or drain cock adapted to be used in connection with the water cooling systems of internal combustion engines, to facilitate the drain of water from the cooling system.

10 In connection with conventional cooling systems for internal combustion engines, the drain cock is generally inaccessibly located, so that it is an extremely tedious operation to open and close the same, resulting in 15 much loss of time and soiling of garments. It is known that the water should be drained from the cooling system frequently, and in winter time when it is not desired to use anti-freeze solutions, the water should be 20 drained during periods when the internal combustion engine is not in use. To permit the facile draining of the water from the cooling system, the improved valve mechanism and operating means therefor has 25 been provided, which may be easily operated by a pedal from the driver's compartment or other similar easily reached location.

Other objects and advantages of this invention will be apparent during the course 30 of the following detailed description.

In the accompanying drawing, forming a part of this specification, and wherein similar reference characters designate corresponding parts throughout the several views,

35 Figure 1 is a side elevation of the improved valve mechanism and operating means therefor as applied to the internal combustion engine of an automotive vehicle.

Figure 2 is a side elevation of the operating details of the invention, showing the same in position for holding the valve open 40 to drain water from the cooling system.

Figure 3 is an enlarged sectional view taken through the valve details of the invention.

45 Figure 4 is a plan view of an operating pedal support of the invention adapted to be located upon some convenient place on the automobile, such as on the floor boards in the driver's compartment.

50 Figure 5 is a plan view of an improved operating lever mounting, showing the same in retained position to normally hold the valve open.

55 Figure 6 is a sectional view taken on the line 6—6 of Figure 5, and showing more

particularly the retaining means for holding the operating lever in position to maintain the valve open.

In the drawing, wherein for the purpose of illustration is shown only a preferred embodiment of this invention, the letter A may generally designate an internal combustion engine, which may be of the water cooled type, and with which the water cooling radiator B may be associated, and connected to the water jacket of the engine A as by a lower conduit C and the conventional upper conduit D. If desired the water cooling system may be of the pump operated 65 type, utilizing a pump E for pumping the water from the radiator thru the conduit C to the water jacket of the engine A. The improved valve mechanism and operating structure may be generally designated by 70 letter K, and comprises the valve structure or drain cock M and the operating means P therefor.

Referring to the structure of the valve M, the same includes a casing 10, of substantially oval-shaped construction, preferably comprising detachable upper and lower parts 11 and 12 respectively, and providing the enlarged valve compartment 13 therein. The upper and lower sections may 80 be detachably connected in any approved manner to facilitate the assemblage of the valve member 14 in the compartment 13. The casing 10 at its upper end is provided with a reduced screw threaded shank 16, 85 having a reduced passageway 17 therethrough, and this reduced shank 16 is adapted for detachable connection in a nipple 20 formed at the lowermost part of the water conduit C, so that the water from both the 90 water jacket of the engine A and the radiator B may drain in its entirety into the valve casing compartment 13. The valve casing 10 at its lower end, and diametrically opposed and axially related to the screw 95 threaded shank 16 provides the valve supporting extension 25 through which the valve member 14 reciprocably extends, in any approved manner, and preferably in a bushing 26, although such need not be provided, but is preferable. This valve member 14 includes the disc-shaped substantially concavo-convex head 28 adapted to seat upon the tapered seat 29 provided at the bottom 100 of the compartment 13, and furthermore includes the straight shank 30 which extends through the passageway of the nipple 25 and 105 110

the bushing 26, and at its lower end extends below the casing 10. The housing 10 is provided with a downwardly inclined drain duct 32, just below the valve seat 29, which is adapted to be closed off from the compartment 13, when the valve 28 is seated, and as is illustrated in Figure 3 of the drawings.

The radial supporting extension 35 is preferably provided at the lower end of the nipple 25, having a link 36 pivotally connected therewith; a connecting lever 37 being pivotally connected at the opposite end of said link. The valve stem 30 at its lower exterior end is pivotally connected at 40 with the lever 37, between the ends of the latter, and a valve spring 41 is disposed axially about the stem 30, under compression between the lever 37 and the nipple 25, to normally force the valve head 28 upon its seat, and as can readily be understood from Figure 3 of the drawing.

Referring to the operating means D, by means of which to lift the lever 37 and lift the valve 14 off its seat, the same preferably comprises a bell crank lever 50, pivotally mounted at 51 in any approved relation upon a support of the engine A or chassis of the vehicle with which the engine is associated. At one end of the bell crank lever 50 a connecting rod 52 is pivotally associated, extending towards the lever 37 and being connected with the lever 37 at a point on the end thereof opposite to the link connected end, by means of a tension spiral spring 55, which is normally under tension to pull the bell crank lever into the position illustrated in Figure 1. At its other end the bell crank lever 50 is pivotally connected to a rod or cable 57, and at its opposite end the connecting rod 57 is pivotally connected at 58 to a pedal or operating lever 59 pivotally mounted upon a special support 60 provided therefor.

The pedal operating lever and support therefor are preferably constructed of sheet metal, and the support 60 generally comprises a rectangular shaped body portion 61, which may be attached as by screws 62 upon the floor board 65 of the vehicle. Adjacent its forward end the support body 61 is provided with the upwardly extending parallel ears 63 for pivotally connecting the lever 59 thereto, as by bolts 66. At the opposite end of the body 61, and at opposite side edges thereof the upwardly extending spring retaining arms 67 are provided, which are arcuated slightly over the body portion 61, to grip the lever 59 when the same is pressed downward at its free end, to retain the same in position to maintain the valve open.

The lever 59 is preferably provided with a pair of upstanding lugs 69 for attachment to the ears 63 by the bolts 66, and said lever

at the end thereof opposite to the connection 58 is upturned, at 70, to facilitate the lifting of the operating lever from the gripping of the same by the fingers 67, merely by the insertion of the toe of a person's foot beneath the upturned end 70 and lifting upwardly.

From the foregoing description of this invention the operation of the improved valve will be apparent. Merely by pressing upon the pedal at its free end the connecting rod 75 57 will be pulled to rock the bell crank lever 50, and through the intermediary of the connecting rod 52, the spring 55, and lever 37, will elevate the valve 14 to lift head 28 off its seat and permit water to drain from the 80 cooling system through the compartment 13 and out of the duct 32.

Various changes in the shape, size, and arrangement of parts may be made to the form of invention herein shown and described, without departing from the spirit of the invention or the scope of the claims.

I claim:

1. In a drain valve the combination of a substantially bulbular casing providing an enlarged compartment therein, said casing at one end having an attaching nipple provided with a communicating passageway therethrough and at the opposite end provided with a nipple having a passageway therethrough, a valve mechanism reciprocatably mounted in the passageway of the last mentioned nipple including a valve head operating in the compartment of said casing and a stem in said passageway, said casing having a drain duct communicating with said compartment and so located that it will be closed off from the compartment when the valve head is seated, a projection carried by said casing, a lever pivoted intermediate its ends to the outer end of the valve stem, a link connected with one end of said lever and with said projection, a compression spring about said valve stem between the lever and said casing, and operating means connected with said lever at the opposite end thereof from said link.

2. In combination with an internal combustion engine cooling system, a drain valve for the cooling system, a spring for maintaining the valve seated, a bell crank lever pivoted upon a support, a connecting rod extending from one end of the bell crank lever towards said valve, a tension spring connected with said connecting rod and acting with a tendency to unseat the valve but with less force than the valve seating action of the first mentioned spring, a lever pivoted between its ends, a connecting rod connecting one end of the lever with the end of said bell crank lever opposite to the end to which the first mentioned connecting rod is attached, and spring fingers for maintaining the lever in position to maintain the valve open.

3. In combination with an internal com-

bustion engine cooling system, a drain valve for said cooling system, spring means normally maintaining the valve closed, a pivoted bell crank lever pivoted remote from the drain valve, a rod connected to one end of the bell crank lever, a spring connected to said connecting rod at its opposite end

and being operatively connected to the drain valve, an operating lever, connecting rod means connecting the operating lever with said bell crank lever, and means to maintain the operating lever in position to open the drain valve. 10

GENUINO ALESI.
